UNITED STATES PATENT OFFICE

FREDERICK A. PRESTON, OF LAKE FOREST, ILLINOIS, ASSIGNOR TO THE P & M COMPANY, OF CHICAGO, ILLINOIS, A CORPORATION OF ILLINOIS

RAIL ANCHOR

Application filed July 2, 1928. Serial No. 289,831.

This invention relates to rail anchors and has for its object to provide an improved one-piece rail anchor having rail gripping means which embraces the base of a railroad rail 5 and maintains its hold on the rail by reason of a combination of a plurality of gripping engagements.

A more specific object is to provide a rail anchor having an under rail portion and inwardly projecting jaws, one of which is so formed as to exert a spring grip both vertically and transversely of the rail and which is adapted to be flexed in applying the anchor to permit the other jaw to be hooked over 15 the upper longitudinal corner of the base at the opposite side of the rail.

Another object is to provide an arrangement of rail gripping surfaces whereby a strong shackle grip transversely of the rail 20 is effected when one end of the anchor is pressed against a cross tie. In this connection the invention contemplates a construction in which the rail gripping members, when in their normal gripping position on 25 the rail, are spaced from each other a distance less than the width of the rail base, whereby one end of the anchor serves as a lever arm to rock the rail gripping members into said shackle gripping engagement with the rail.

30 Another object is to provide an anchor of the above character in which the transverse spring grip is produced by a reflex action transversely of the rail of previously distorted parts of the anchor. The invention 35 also contemplates a combination transverse spring grip, one component of which is produced by a direct reflex action of a resilient part of the anchor as above noted, and the other component of which is produced by a 40 vertical reflex action of the spring jaw exerting its pressure downwardly against an inclined surface of the base. A further object 45 is to provide, in an anchor of the above general type, a jaw construction having a relatively large range of flexing limits without impairing its holding qualities. A still further and more specific object is to provide an improved rail anchor in which one jaw bears against the web of the rail and the 50 other jaw hooks over the upper edge of the

base at the opposite side of the rail, the distance between said jaws being such that they are spread apart when in their normal applied position on a rail so as to exert transverse spring pressure directed against the 55 lower portion of the web of the rail and against one vertical edge portion of the rail base. In this connection the invention contemplates the provision of a jaw portion in the form of a hook in which the hook end 60 provides a tie abutment which extends downward a substantial distance from the bottom surface of the rail base.

The invention has for a still further object 65 such other new and improved constructions hereinafter described and claimed for carrying out the above stated objects and such other objects as will appear from a detailed description of the embodiments shown in the accompanying drawings.

70 The invention is illustrated in two specific embodiments in the accompanying drawings wherein:

Fig. 1 is a plan view of the base portion of a railroad rail showing a rail anchor constructed in accordance with this invention 75 applied in its operative position on the rail base and bearing against the cross tie on which the rail is supported.

Fig. 2 is a side view of the rail anchor device showing one position which it assumes 80 during its application to a rail.

Fig. 3 is a view similar to Fig. 2 showing the rail anchor after it has been forced to its 85 fully applied position.

Fig. 4 is an end view of the rail anchor shown in Fig. 3 illustrating the jaw end thereof so as to show the manner in which the hooked shaped end provides an extended bearing face or tie abutment for the anchor 90 device.

Fig. 5 is a side view of a modified form of the invention showing the anchor in its 95 fully applied position, the base portion of the rail being shown in section.

The embodiment of the invention shown in Figs. 1 to 4 inclusive of the drawings consists preferably of a single bar of resilient metal bent to provide an under-rail portion 10 and formed with a relatively large hooked 100

end portion 11 which embraces the base flange 13 at one side of the rail and bears at the extremity of the hook against the lower portion of the web 14 of the rail. The other 5 end of the bar is formed with a smaller hooked end 15 which is adapted to be sprung over the upper longitudinal corner of the rail base when the anchor is in its fully applied position. The bend 16 forming the large jaw 10 11 is preferably so formed as to provide a substantial clearance 17 between the under surface of the jaw 11 and the upper surface of the rail base flange and to also provide a substantial clearance between the edge 13^a of 15 the rail and the root 18 of the bend 16, thereby providing sufficient clearance to permit substantial vertical flexing of the jaw 11 and bend 16 and also permitting the bend to be flexed a substantial distance if need be transversely of the rail without coming into contact with the vertical edge 13^a of the rail base. The said bend 16 also extends downwardly from the base flange of the rail so as to provide a substantial tie-abutting portion 20 indicated by the reference character 19 adapted to bear against the vertical face of the cross tie at one end of the anchor. In applying the anchor device to the base portion of the rail the hook end or jaw 11 is 25 first hooked over one edge of the base flange as indicated in Fig. 2 of the drawings. In this position the short jaw 15^a is positioned under the base flange at the opposite side of the rail. By applying pressure to the 30 bend 16, this portion of the anchor is flexed so as to provide an effective lengthening of the under rail portion 10 and thereby permits the small jaw 15^a to clear the edge of the rail and snap by the resiliency of the metal into 35 spring gripping engagement with the upper corner portion of the base flange. When the device is in its fully applied position the extremity 20 of the jaw 11 bears against the side face of the web 14 of the rail at a point 40 adjacent the rail base, the lower corner of the jaw 11 being rounded to fit the curved portion of the base at its juncture with the vertical web 14. The flexing action of the hooked 45 end 16 during the application of the anchor to the rail is such that when the anchor is applied the reflex action of the bend 16 exerts a transverse spring pressure against the web 14 of the rail and against the edge and upper surface of the rail base at the opposite side 50 of the rail. There is also a transverse spring grip produced by reason of the downward pressure of the jaw 11 on the inclined upper surface 13^b of the rail base and the bearing of the upper portion of the under rail portion 10 against the bottom surface of the rail base. The tie abutting portion 19, extending 55 a substantial distance below the lower surface of the rail base bears firmly against the bottom surface of the rail. The extremity 60 of the jaw 11, it will be noted, bears against

the upper inclined surface of the rail base at a point disposed a substantial distance inwardly from the bottom bearing point 21 thereby providing a rocking action about a longitudinal axis tending to force the bottom or under rail portion 10 firmly against the bottom surface of the rail not only at the point 21 but also at the point 22 adjacent the small hook end 15. The jaw 15^a resists any tendency that the downward pressure of the bend 19 against the ballast of the roadbed may have to impart a reverse rocking movement about the point 21. The position of the large bend 16 relative to the extremity 20 of the jaw 11 and the bearing surfaces of the hook end 15 form in effect a lever arm which, when the cross tie extends diagonally across the said base, bears against the cross tie adjacent one edge of the rail base whereby the creeping force exerted against the tie through the hook end 16 tends to exert a strong shackle grip on the web 14 and the longitudinal edge portions of the flange 23 of the rail. 70 75 80 85 90

In Fig. 5 a modified embodiment is shown in which the jaw end 11^a and the jaw end at the opposite edge of the rail base are substantially the same in construction and operation as the corresponding members of the embodiment shown in Figs. 1 to 4 inclusive. The modified construction, however, is provided with a downwardly bowed portion 24 between the bottom bearings 21^a, 22^a of the anchor device so as to provide a tie abutting surface extending substantially across the bottom surface of the rail base which extends a substantial distance downwardly from the rail. The said tie abutment, by its engagement with the cross tie 25 will convert any longitudinal pressure on the rail into a shackle gripping action of the anchor device on the top and bottom surfaces of the rail base so as to add to the gripping force heretofore described. The downwardly bowed portion 24 provides also an arc which relieves the bend 16 of a substantial portion of the flexing strain produced when the anchor is subjected to the shackle grip transversely of the rail. That is to say when the extremities of the jaw 11^a and jaw 15^b are forced into shackle gripping engagement with the web and edge portion, respectively, of the rail base. 95 100 105 110 115 120

In other respects the embodiment shown in Fig. 5 may be and preferably is the same as that shown in Figs. 1 to 4 inclusive of the drawings.

While the invention is described in connection with two specific embodiments, these embodiments will readily suggest other modifications to persons skilled in this art. It will be understood therefore that the invention is not to be limited to the specific constructions shown and described except insofar as the claims are expressly limited.

I claim:

1. A rail anchor comprising an under rail 130

portion for bearing against the bottom surface of the rail, a jaw at one end resiliently bearing against the vertical web of the rail, and an inwardly projecting jaw at the other end of said under rail portion adapted to bear against the edge portion of the rail base at the opposite side of the rail.

2. A rail anchor comprising a bar for extending across beneath the base of a rail, jaw means at one end of the bar for engagement with the top face of the rail base at one side of the rail, and gripping means at the other end of the bar for engaging the top and bottom surfaces of the rail base at locations spaced inwardly from the edge thereof and for bearing against the vertical web of the rail.

3. A rail anchor comprising a bar formed at one end with a jaw for engagement with one edge of the rail base and provided at the other end with a hook portion extending around the opposite edge of the rail base without gripping the marginal portion thereof but bearing against the vertical web of the rail, whereby pressure applied longitudinally of the rail against said hook end of the anchor effects a shackle grip of said jaw and the extremity of said hook upon the edge of the base and the vertical web respectively of the rail.

4. A rail anchor comprising a bar formed at one end with an inwardly projecting jaw for engagement with one edge of the rail base and formed at the other end with a relatively long hook portion extending around the opposite edge of the rail base without gripping the marginal portion thereof but bearing against the vertical web of the rail, whereby pressure applied longitudinally of the rail against one end of the anchor effects a shackle grip between the extremity of said hook and said jaw transversely of the rail.

5. A rail anchor comprising a bar for engagement with the bottom surface of the rail base, formed at one end with a small jaw for engagement with the top face of the base flange at one side of the rail and formed at the other end with a hook portion adapted to be forced into spring gripping engagement with the top and bottom surfaces of the base flange at the other side of the rail and into gripping engagement with the vertical web of the rail, the bend of the hook being relatively large and adapted to flex to permit engagement of the small jaw with the edge of the rail base.

6. A spring metal rail anchor comprising a bar for bearing against the bottom of the rail base, formed at one end with a hook portion adapted to be forced into spring gripping engagement with the top and bottom surfaces of the rail base and formed at the other end with a jaw adapted to be snapped into engagement with the top surface of the rail base by the reflex of said hook portions.

7. A spring metal rail anchor comprising

a bar for bearing against the bottom of a rail base, formed at one end with a hook portion adapted to be forced into spring gripping engagement with the top and bottom surfaces of the rail base and formed at the other end with a jaw adapted to be snapped into engagement with the top surface of the rail base by the reflex of said hook portion; the said hook being formed with clearance adjacent the edge of the rail base and adapted to bear against the web of the rail whereby movement of one end of the anchor relative of the rail in a direction longitudinally of the rail effects a shackle grip of the device on the web of the rail and one base flange thereof.

8. A rail anchor comprising a bar extending across beneath the rail base and bowed downwardly intermediate its ends to provide spaced bearing surfaces for engagement with the bottom surface of the rail base adjacent the opposite longitudinal edges thereof and to form a tie bearing face which extends a substantial distance below the bottom surface of the rail, one end of the bar formed with a jaw which cooperates with one of said bottom bearings to grip the top and bottom surfaces of the rail base at one side of the rail and formed at the other end with a hook shaped portion providing a downwardly bowed tie abutting portion adjacent the end of the anchor and providing also an inwardly projecting jaw for bearing against the upper inclined surface of the rail base and the vertical web of the rail, the distance between the extremity of said hook and said first mentioned jaw being normally less than the distance between the surfaces engaged thereby, whereby the said extremity of the hook and the said jaw exert spring pressure transversely of the rail when the anchor is in its applied position.

9. A rail anchor comprising a body provided at one end with a base flange embracing hook which bears at its extremity upon the fillet between said flange and the vertical web of the rail, which hook includes a downwardly extending tie abutting portion providing a substantial clearance between the hook and the bottom marginal surface of the base flange embraced, means at the other end of the body for embracing the other edge of the rail base, provided with a portion overlying the upper corner of said edge to prevent upward pressure exerted against said tie abutment from displacing said edge engaging means.

10. A rail anchor comprising a body provided at one end with a base flange embracing hook which bears at its extremity upon the fillet between said flange and the vertical web of the rail, which hook includes a downwardly extending tie abutting portion providing a substantial clearance between the hook and the bottom marginal surface

of the base flange embraced, a shoulder at the other end of the body for engaging the vertical edge portion of the rail base at the other side of the rail, which shoulder is so positioned relative to the end of said hook that it is necessary to distort a portion of the anchor in forcing the shoulder to its applied position, and means for preventing upward pressure exerted against said abutment from displacing said shoulder.

11. A rail anchor comprising a body formed at opposite ends with rail engaging means which when in their applied positions exert a spring grip diagonally through the base portion of the rail, one of said means being formed to provide a tie abutting portion which extends downwardly a substantial distance below the bottom surface of the rail base and the other of said means being provided with a portion overlying the upper corner of the rail base to prevent displacement of said last named means during the presence of upward pressure against said tie abutting portion.

12. A rail anchor comprising a body formed at opposite ends with rail engaging means which when in their applied positions exert a spring grip diagonally through the base from the fillet between the base and vertical web at one side of the rail to the lower corner of the base at the other side of the rail, one of said means being formed to provide a tie abutting portion which extends downwardly a substantial distance beneath the bottom surface of the rail base and the other of said means being provided with a portion overlying the upper corner of the rail base to prevent displacement of said last named means during the presence of upward pressure against the tie abutting portion.

13. A rail anchor comprising a body formed at opposite ends with rail-engaging means which when in their applied positions exert a spring grip diagonally through the base portion of the rail, one of said means being formed to provide a tie abutting portion which extends downwardly a substantial distance beneath the bottom surface of the rail base, and the other of said means being provided with a portion so formed and positioned relative to the other parts of the anchor as to prevent displacement of said last named means during the presence of upward pressure against said tie abutting portion.

14. A rail anchor comprising a bar having a portion for bearing against the bottom surface of the rail and formed at one end with a gripping means for engaging over the upper corner portion of the rail base flange at one side of the rail, and formed at the other end with a resilient hook portion for embracing the rail base flange at the other side of the rail and adapted to be flexed both vertically and

transversely of the rail in forcing the anchor transversely of the rail to its normal gripping position, the extremity of said hook being formed to bear against the vertical web of the rail when the anchor is in its fully applied position.

15. A rail anchor for application to a rail by movement transversely of the rail from one side thereof and comprising a body portion provided at one end with means for engaging over the upper corner portion of the rail base flange at one side of the rail and provided at the other end with a relatively long resilient hook portion formed to provide clearance between the inner face of the hook and the adjacent edge of the rail base and formed at the extremity of the hook with a bearing surface which is forced by the resiliency of the anchor into gripping engagement with the vertical web of the rail.
